UNITED STATES PATENT OFFICE.

WILLIAM VOGEL, OF NEW YORK, N. Y.

CAN-OPENER.

1,381,037.

Specification of Letters Patent. Patented June 7, 1921.

Application filed August 17, 1920. Serial No. 404,124.

To all whom it may concern:

Be it known that I, WILLIAM VOGEL, a citizen of the United States, and a resident of the borough of Manhattan, county, city, 5 and State of New York, have invented certain new and useful Improvements in Can-Openers, described and claimed in the annexed specification.

This invention relates to can openers, of 10 the type employed to open cans, the covers of which have to be rolled back and thereby forcibly torn loose from the body of the can.

An object of the invention is to provide an 15 improved can opener as a permanently reusable tool of this type, which may be manufactured at minimum cost and preferably by automatic machinery such as a punching or stamping machine.

20 Other objects of the invention reside in the improvement of the details of construction of such a can opener.

This will all better be understood by reference to the illustrative embodiment of the 25 invention described in the specification in connection with the accompanying drawings which form a part hereof, and which are set forth merely for purposes of illustration and not limitation. Like characters designate corresponding parts in the drawings in which—

Figure 1 is a perspective view;

Fig. 2 is a plan view of the tool with parts 30 broken away and drawn to an enlarged scale;

Fig. 3 is a side elevation with parts shown in section and otherwise corresponding to Fig. 2;

Fig. 4 is a view corresponding to Fig. 3 but showing the jaw member before its 40 assemblage; and

Fig. 5 is a sectional view with parts shown in elevation of the assembled tool.

It is usual practice to provide a key having a closed ended slot to engage the lip 45 of cans, the tops of which are to be ripped loose by rolling them back about the key, but it has been found in practice that the top of the can usually breaks loose before it has been completely severed from the can, 50 with the key wrapped up in the enveloping sheet-metal so that it cannot be used again. One tool disclosed in the patent to Arnold, No. 1,095,369, patented May 5, 1914 has been disclosed in an attempt to overcome the 55 disadvantages of the usual key for opening cans but this Arnold tool is costly to manu-

facture as it requires the employment of a special casting or forging which must be end slotted. In carrying out my invention, I have designed a better tool in an operative 60 sense than that of Arnold and in addition one which may be manufactured at much less cost.

A flat blade 1 is stamped out of sheet-metal such as sheet steel, and extends rearwardly into the shank 2, to which an operating handle 3 may be fitted and secured as by the pin 4. The forward end of the blade 1 has the tapering operating portion 5, at the rear of which is provided a perforation 6, 65 preferably rectangular and preferably having flaring walls 7 which flare toward the side 80 of the shank 1. The flaring may be provided by suitably shaping the punch which operates in the stamping of the blade 75 blank. A jaw member 8 likewise stamped from sheet metal such as sheet steel which may be the same stock from which the blade 1 is stamped, has a butt portion 9 provided with an outstanding boss 10, adapted to 80 fit the perforation 6 of the blade 1. A forwardly tapering jaw 11, the surface 12 of which is offset from the surface 13 of butt 9, parallels the surface 14 of operating end 5 of blade 1, to provide the open ended slot 15. 85

An outward flaring for the slot 15 may be provided at the nose 16 to provide an entrance mouth 17 for the lip of the can top. As shown, it is preferred that the nose 16 terminate just short of the nose 21 for the 90 operating end 5 of blade 1. This facilitates picking up the lip of the can top.

The general forward taper of the entire operating end A of the tool facilitates the removal of the tool from a can cover, after 95 same has been rolled loose from the can.

If desired, one or more additional perforations 60 and coöperating bosses 100 may be provided for the butt 9 as indicated in Fig. 5, although it is to be understood that 100 boss 10 may be of any desired longitudinal extent. The beveling of the operating end A may be formed automatically with an emery grinder and is preferred as it provides an initial sharp bend to the cover lip helping to hold same attached to the tool. However the beveling may be omitted, entirely with the finished configuration of the tool solely such as may be imparted by the punching or stamping operation upon the 105 two parts of the tool, the blade and the jaw member.

What I claim and desire to secure by United States Letters Patent is:

1. A can-opener comprising a stamped sheet metal blade having a flat relatively broad shank tapering forwardly at its operating end and having a perforation in said shank; a stamped sheet metal jaw member having a butt portion provided with a boss fitting through said perforation and riveted therein and having a jaw forwardly tapered, offset from said operating end extending forwardly and adjusted thereto and providing an open ended slot for the entrance of the lip of a can to be opened.
2. A can-opener comprising a stamped sheet-metal blade having a flat relatively broad shank tapering forwardly at its op-

erating end and having a central rectangular perforation in said shank; a stamped sheet-metal jaw member having a butt portion centrally overlying said shank with the 20 butt portion provided with a boss fitting through said perforation and riveted therein and having a jaw forwardly tapered, offset from said operating end extending forwardly and adjusted thereto and providing 25 an open ended slot for the entrance of the lip of a can to be opened.

In witness whereof, I have signed my name to this specification this 6th day of August, 1920.

WILLIAM VOGEL.
